CLAIM

The ornamental design for an air deodorizing apparatus as shown and described.

DESCRIPTION

1. Air deodorizing apparatus

1.1: Perspective

1.2: Front

1.3: Right

1.4: Back

1.5: Top

1.6: Bottom

(Continued)

The broken lines shown in the figures are for the purpose of illustrating portions of the air deodorizing apparatus and form no part of the claimed design.
